CLAIM

I claim the ornamental design for an agitator, as shown and described.

DESCRIPTION

FIG. 1 is a front perspective view of an agitator showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 1;

FIG. 10 is an enlarged view of the encircled portion in FIG. 1; and,

FIG. 11 is a front perspective view of the agitator in which the pulsator portion is shown in dot-dash broken lines to illustrate an example environment.

The evenly dashed broken lines in the figures depict portions of the agitator which form no part of the claimed design. The dot-dash broken lines in FIG. 11 depicts environmental subject matter and forms no part of the claimed design. The dot-dot-dash broken lines encircling portions of the claimed design that are illustrated in enlargements form no part of the claimed design.
